UNITED STATES PATENT OFFICE

2,325,281

BOX

Louis H. Schleicher, St. Louis, Mo.

Application January 21, 1941, Serial No. 375,185

2 Claims. (CL 229—8)

This invention relates to boxes; and has special reference to boxes or cartons made of cardboard or the like and having protruding portions in connection with the side walls thereof.

An object of the invention is to provide a box made of cardboard or like material and of any desired cross-sectional form and having outwardly extended formations in connection with the side walls thereof and at any desired locations about the box and which may also be extended downwardly below the box bottom to provide supporting legs whereby the box bottom is held out of contact with the support upon which the legs rest. However, these outwardly extended formations may be of any desired lengths and of various forms, at the option of a maker or user.

Another object of the invention is to provide an improved box made of cardboard or the like having adjacent portions or panels of its side walls connected by outwardly extended portions located at the corners of the box or elsewhere about the box as desired, and cooperating with a bottom attached to said wall portions or panels to retain them and the outwardly extended portions in relatively fixed relationship.

Another object of the invention is to provide an improved box made of cardboard or the like and having its adjacent side walls angularly disposed relative to each other and connected together at the corners by outwardly extended portions that may be formed integral with the side walls and may, if desired, be extended downwardly to function as legs for retaining the box bottom out of contact with the support upon which the legs rest.

Various other objects and advantages of the invention will be apparent from the following description, reference being made to the annexed drawing, in which—

Fig. 1 is a plan view of one form of a blank that may be used in making a box embodying the present invention.

Fig. 2 is a perspective view of a box proper made from the blank shown in Fig. 1.

Fig. 3 is a vertical cross-sectional view of a box like that shown in Fig. 2 and having a removable lid thereon.

Fig. 4 is a horizontal cross-sectional view of the box shown in Figs. 2 and 3.

The side walls of the box or carton are made of a blank of cardboard or like material. The walls comprise a number of adjacent panels or sides, and the blank may be shaped to form a box of any selected cross-sectional form. The

material used is preferably flexible so that the panels or side walls may be curved or not, as desired.

The blank shown in Fig. 1 is of a shape and design to constitute the side walls and outwardly extended formations in connection therewith to form a box generally of the shape shown in Figs. 2, 3 and 4. However, it is apparent that boxes of various other shapes may be formed by use of this invention merely by varying the blank or blanks constituting the side walls. Said blank comprises a number of panels or side walls 1 formed in longitudinal series and connected together by outwardly extended formation 2 having downwardly diverging score lines 3 along the lines of their union with the respective panels, and also having score lines 4 between the scores 3. The score lines 4 diverge downwardly from each other and from the lines 3. Thus the blank may be bent along the scores 3 and 4 to arrange the panels or side walls 1 in the desired relationship to provide the upwardly extended enclosing wall of a box or carton (Fig. 2). In the specific form of box shown, the downwardly flaring and outwardly extended formations 2 are at the corners of the box, which is approximately rectangular in cross-section, although it is clear that various cross-sectional forms of box may be provided, as desired. Further, the walls 1 may be made of the same length or of different lengths, as desired. The formation 2 at one end of the blank may overlap an extended flange 5 at the opposite end of the blank and be attached thereto by cement 6 or other fastening means (Fig. 4).

The two downwardly diverging lines 3 and the two intermediate lines 4, which are between the lines 3 and diverge downwardly from each other and also from said lines 3, provide a novel formation at each corner of the box. The formation at each corner of the box consists of three walls two of which are connected with the ends of the adjacent side walls of the box along the score lines 3, and the other one of which three walls integrally connects said two walls. This is indicated on the blank (Fig. 1) and also is clearly apparent in Fig. 4 of the drawing.

The bottom 7 of the box is secured within the enclosure formed by the side walls 1, and is attached to said side walls by any appropriate fastening means, such as marginal flanges 8, along the edges of the bottom wall seating against and attached to the inner surfaces of said side walls. The corners of the bottom 7 extend into the spaces between the adjacent

ends of the walls 1 provided by the outwardly extended formations 2. The bottom 7 attached to the side walls of the box in this way holds the side walls in proper relationship and substantially prevents further bending of the walls along the scores 3 and 4. The bottom 7 may be approximately even with the lower edges of the side walls 1, as shown in Fig. 3; or said bottom may be secured in any other preferred position within the space provided by said side walls.

As shown, the formations 2 extend below the lower edges of the side walls and below the bottom 7 and function as legs to uphold the box in a position in which the bottom 7 is spaced above and out of contact with the support on which the box is resting. However, it is apparent that the length of the formations 2 may be reduced to leave the bottom 7 free to rest upon the support. A lid 9 is provided for the box and is formed with a projecting portion 10 extending in the upper end of the box enclosure to engage with the inner sides of the wall 4 and thereby hold the lid in position on the box.

From the foregoing, it is apparent that my improved box attains all of its intended objects and purposes efficiently and economically; that the enclosing wall blank may be made in a single piece or otherwise, as desired; and that the formations 2 may be caused to function as supporting legs for the box or not, as desired. Further, the construction and arrangement of the parts may be varied otherwise than as specifically mentioned and within the scope of the appended claims without departure from the nature and principle of the invention.

I claim:

1. A polygonal box made of cardboard and comprising an elongated blank including a series of panels constituting side walls, three downwardly flaring corner wall portions integrally connecting adjacent ends of said side wall panels and extending outwardly from the corners of the box and forming enclosed spaces within the box and also extending beyond the lower edges of said side walls to form supporting legs, and a bottom attached to said side walls and having corners extending into and substantially closing the inner central portions of said spaces.
2. In a cardboard box, a series of four side walls arranged in angular relationship to form an enclosed space and having each two walls that are opposite from each other diverging downwardly, two outwardly diverging wall portions integral with the ends of each of said four walls and of gradually increasing width from their upper ends to their lower ends and extending downwardly beyond the lower edges of said walls and forming legs, a single flat wall portion integrally connecting the outer edges of each adjacent pair of said first wall portions and of equal length therewith and being of gradually increasing width from its upper to its lower end, a separate bottom fitted within said enclosed space formed by said walls and having corners extending into the spaces provided by said wall portions at the adjacent ends of said side walls, and flanges integral with the edges of said bottom attached to the inner surfaces of said side walls.
